UNITED STATES PATENT OFFICE

113,096

DESIGN FOR A TEXTILE FABRIC

Samuel E. Staines, Ridgewood, N. J., assignor, by
mesne assignments, to Reconstruction Finance
Corporation, New York, N. Y., a corporation of
the United States

Application December 13, 1937, Serial No. 73,556

Term of patent 14 years

To all whom it may concern:

Be it known that I, Samuel E. Staines, a citizen of the United States, residing at 309 Stevens Avenue, Ridgewood, in the county of Bergen and State of New Jersey, have invented a new, original, and ornamental Design for Textile Fabrics, of which the following is a specification, reference being had to the accompanying drawings, forming part thereof.

The figure of the drawing is a plan view of a piece of textile fabric having the design woven therein.

The design of this case is characterized by two sets of uniformly spaced depressed stripes crossing each other at right angles, with nubs located within small rectangles defined by crossing stripes, producing the appearance of diagonal stripes extending in one direction only, one set of the depressed stripes being more pronounced than the other.

I claim:

The ornamental design for a textile fabric, as described and shown.

SAMUEL E. STAINES.
